UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,962, dated July 1, 1890.

Application filed April 15, 1890. Serial No. 348,121. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown an elevation of my improved cane or umbrella handle embodying the new design forming subject-matter of this application.

15 A is the body part, and is substantially vertical and more or less cylindrical, with a slight swelling at the top, as at E, and terminating in a plain head B, slightly curved. The body part A E is formed with a series of vertical ribs D, which extend down more at the sides 20 G than at places between them. The space

of the body part below the lower edges of these vertical ribs is highly ornamented, as at F. The lower part of the body part A is drawn slightly inward and terminates in a plain bead or band C. Both sides of the handle are substantially the same.

25 The handle is made of any suitable material.

Having now described my new design, what I claim as new, and desire to secure by Letters Patent, is—

The design for umbrella or cane handles, substantially as herein described and shown.

In testimony of which invention I have hereunto set my hand.

HENRY O. SCHMIDT.
